DESIGN FOR A DRAG ANGLE FINDER FOR DIAMOND DRESSING TOOLS

Fred Bley, Chicago, Ill.

Application August 19, 1943, Serial No. 110,961

Term of patent 14 years

To all whom it may concern:

Be it known that I, Fred Bley, a citizen of the United States, residing at Chicago, in the county of Cook and State of Illinois, have invented a new, original, and ornamental Design for a Drag Angle Finder for Diamond Dressing Tools, of which the following is a specification, reference being had to the accompanying drawing, forming a part thereof.

Referring to the drawing:

Fig. 1 is a front elevational view of a drag angle finder for diamond dressing tools, showing my new design; and

Fig. 2 is a top plan thereof.

I claim:

The ornamental design for a drag angle finder for diamond dressing tools, as shown.

FRED BLEY.
